UNITED STATES PATENT OFFICE.

CHARLES E. BENNETT, OF ATLANTA, GEORGIA, ASSIGNOR TO THE SERVICE ENGINEERING COMPANY, OF MARIETTA, GEORGIA, A CORPORATION OF GEORGIA.

CURRENT INTERRUPTER.

1,420,515.

Specification of Letters Patent. Patented June 20, 1922.

Application filed September 9, 1919, Serial No. 322,645. Renewed November 18, 1921. Serial No. 516,245.

To all whom it may concern:

Be it known that I, CHARLES E. BENNETT, a citizen of the United States, residing at Atlanta, in the county of Fulton and State 5 of Georgia, have invented certain new and useful Improvements in Current Interrupters, of which the following is a specification.

My invention relates to current interrupters and particularly an interrupter of the 10 type disclosed in my copending applications 207,771, filed December 18, 1917; 247,826, filed August 1, 1918, and 298,273, filed May 19, 1919, the object of my invention being to 15 provide a construction having certain structural features which facilitate not only initial manufacture but also repair and exchange of parts to accommodate the interrupter to an increased or decreased voltage on the line protected.

20 In the accompanying drawing

Fig. 1 is a front elevation of an apparatus in which my invention is illustratively embodied.

25 Fig. 2 is an elevation of the interrupter element detached, and

Fig. 3 is a longitudinal section through one end of the interrupter element drawn to a larger scale.

As here shown the structure comprises an 30 elongated rectangular base 12 of insulating material, having mounted on its face in opposite corners of one end, a pair of terminal plates 13 and 14. The plate 13 carries a binding terminal 15 to which is secured the 35 lead 1 from the power line to be protected; and also a set screw 16 passing through the slot 17 in the base 18 of the horn 2^a of a horn gap. The other plate 14 also carries a set screw 19 which serves not only to secure the 40 slotted base 20 of the other horn 2^b but also to secure one end of a connecting strip 3.

45 A second pair of terminal plates 4^a and 4^b mounted on the base, carry not only binding terminals 21 and 22 but also spring terminal clips 23 and 24. The connecting strip 3 is secured to the terminal 21 of plate 4^a while the ground lead 11 is connected to the terminal 22 of plate 4^b. Detachably engaged with the spring clip 23 and 24 are the blade contacts 10^a and 10^b of the interrupter element.

The latter as here shown comprises a liquid container in the form of a glass tube 5 closed at its opposite ends by caps 6^a and 6^b and preferably of insulating material.

An inner tube 7, also of glass, is suspended 55 from the upper cap 6^a and dips into the liquid in the container, forming an expansion chamber in which the arc is drawn. The arcing terminal 8 is mounted at the lower end of the conductor rod 9 which is 60 formed in one with or secured to the blade contact 10^a at the top cap 6^a of the interrupter. The blade 10^b of the lower cap 6^b extends through the latter into contact with the electrolyte in the tube 5, or the cap 6^b 65 may be entirely of metal if preferred.

Vents 25 in the cap 6^a maintain the space above the liquid in tube 5 at atmospheric pressure, while a small vent 26 opening to the interior of the tube 7 not only prevents 70 excessive pressure therein when the arc is drawn and vapors formed but insures the re-establishment of the atmospheric pressure therein also after the arc is broken and the vapors have cooled. The apparatus thus 75 automatically resets after the arc is broken.

The construction illustrated is of particular practical value since it permits the apparatus to be not only readily repaired in case of injury to the interrupter element, but 80 also readily altered to meet different voltage conditions on the line protected. If either of the tubes 5 or 7 break, the interrupter may be removed and replaced in a moment's time by a fresh one of the same capacity; 85 while if the line is to have a greater or lesser normal voltage imposed upon it, then the replaced interrupter will differ in its adjustments to meet the new voltage conditions. The horns 2^a and 2^b are adjustable in their 90 spacing to the requirements of the normal load on the line and may be readily shifted together or apart as need be.

The apparatus shown, while simple and efficient, may be readily modified in the details of its construction without departing from what I claim as my invention.

I claim:

1. An automatic current interrupter comprising a liquid container, an expansion 100 chamber therein, a terminal adapted to draw an arc in said chamber, an exterior contact electrically connected to said terminal, a second exterior contact electrically connected to the liquid in said container, in combination with a base, a pair 105 of terminals mounted thereon and means for establishing a quick detachable connection

between said terminals on the base and the exterior contacts of the interrupter.

2. An automatic current interrupter comprising a liquid container, an expansion chamber therein, a terminal adapted to draw an arc in said chamber, an exterior contact electrically connected to said terminal, a second exterior contact electrically connected to the liquid in said container in combination with a base, a pair of terminals mounted thereon and means for establishing a quick detachable connection between said terminals on the base and the exterior contacts of the interrupter, together with a pair of cooperating gap terminals mounted on said base and a connection from one of said gap terminals to one of the interrupter-receiving terminals.
3. An automatic current interrupter comprising a liquid container, an expansion chamber therein, a terminal adapted to draw an arc in said chamber, an exterior contact electrically connected to said terminal, a second exterior contact electrically connected to the liquid in said container, in combination with a base, a pair of terminals mounted thereon and means for establishing a quick detachable connection between said terminals on the base and the exterior contacts of the interrupter, together with a pair of cooperating gap terminals mounted

on said base, and spaced adjustably apart and a connection from one of said gap terminals to one of the interrupter-receiving terminals.

4. In an automatic current interrupter, a liquid container, an expansion chamber therein, an arcing terminal arranged in said chamber, an exterior contact for said terminal, and a second exterior contact in electrical connection with the liquid in said container in combination with a support and a pair of spaced terminals thereon adapted to make quick detachable connection with the exterior contacts of the interrupter.

5. In an automatic current interrupter, a liquid containing tube, heads closing the opposite ends thereof, an inner tube supported in one of said heads and extending toward but spaced from the other head, an arcing terminal arranged within said inner tube, an exterior contact projecting from one of said heads and in electrical connection with the arcing terminal in the inner tube, together with a second exterior contact carried by the other head and in electrical connection with the liquid in the container.

In testimony whereof I have signed my name to this specification.

CHARLES E. BENNETT.
